DIFFUSER

Lawrence P. Mellyn, Glocester, R.I., assignor to General Electric Company

Filed Sept. 28, 1973, Ser. No. 401,574

Term of patent 14 years

Int. Cl. D26—05

U.S. Cl. D48—16 D

FIG. 1

FIG. 2

FIG. 3

FIG. 4

FIG. 5

FIG. 6

FIG. 7

© General Electric Company 1976. The drawings of this patent document contain material to which a claim of copyright is made. The copyright owner, assignee herein, has no objection to the duplication of the patent drawing but reserves all other copyright rights whatsoever. A certified copy of the certificate of copyright registration as registered by the U.S. Copyright Office is in the file of the application of this patent.

FIG. 1 is a perspective view of a diffuser showing my new design;

FIG. 2 is a front elevational view of a diffuser as in FIG. 1 but on an enlarged scale;

FIG. 3 is a side elevational view of the diffuser of FIG. 2;

FIG. 4 is a side elevational view of the other side thereof;

FIG. 5 is a rear elevational view thereof; FIG. 6 is a top plan view thereof; and FIG. 7 is a bottom plan view thereof.

I claim:

The ornamental design for a diffuser, as shown and described.
